UNITED STATES PATENT OFFICE.

ALBERT EDWARD COLLYER, OF MONMOUTH, ILLINOIS, ASSIGNOR OF ONE-HALF TO ORRISON TOBIAS KIMMEL AND BENJAMIN G. KIMMEL, OF SAME PLACE.

AUTOMATIC TELEGRAPH-REPEATER.

SPECIFICATION forming part of Letters Patent No. 558,042, dated April 14, 1896.

Application filed December 26, 1893. Serial No. 494,734. (No model.)

To all whom it may concern:

Be it known that I, ALBERT EDWARD COLLYER, a citizen of the United States, and a resident of Monmouth, Warren county, State of Illinois, have invented certain new and useful Improvements in Automatic Telegraph-Repeaters; and my preferred manner of carrying out the invention is set forth in the following full, clear, and exact description, terminating with claims particularly specifying the novelty.

This invention relates to telegraphy, and more especially to instruments used in that art and which are known as "repeaters;" and the object of the same is to produce an instrument of this character which will repeat without the use of a local battery and will steady the current, and one that can be used at the point of crossing of two lines—say north-south and east-west—so as to permit an operator on either line to communicate with another operator either on the same line or on the other line.

To this end the invention consists, essentially, of two common relays or electromagnets whose armature-levers carry inwardly-projecting lugs, a single rocking bar mounted between said levers and having an inclined and a flattened portion at each end adapted to be engaged by one of said lugs, springs holding said bar in a normally-horizontal position and at that time making contact with posts, and means for permitting the bar to be turned on a vertical pivot, so as to throw its ends out of line with and hence out of control of said lugs, but yet not to throw its springs out of contact with their posts, the whole being designed for use as and of the specific construction set forth in the following specification and illustrated in the drawings, wherein—

Figure 1 is a side elevation of this repeater, partly in section, and also a diagram showing the circuits and connections. Fig. 2 is a plan view of the repeater with its bar turned slightly, so as to be out of engagement with and control of the lugs on the armature-levers.

Referring to the said drawings, the letter R designates my improved repeater, from the center of whose base rises a tubular socket 1, having in one side a laterally-elongated slot

2, and 3 is a cylindrical stem which fits loosely in said socket, while a set-screw 4 passes through said slot and screws into the stem. The head of said stem is forked, as at 5, and the arms of the fork carry the usual screw-bearings 6, projecting inward and held in place by jam-nuts 7.

8 is a horizontal bar of insulating material, having across its center a journal 9, with pointed ends engaging said bearings 6, so that the bar can rock thereon. At the ends of the bar depend hooks 10, which support the outer ends of springs E³ N³, whose inner ends are secured by screws 11 to the lower side of the bar near its center, and set-screws 12 with jam-nuts 13 pass downward through the bar for adjusting the springs, as will be clear. Rising from the base at proper points are posts E⁴ N⁴, which normally make contact with the outer end of said springs just inside of the hooks 10, as seen.

e⁸ n⁸ are two electromagnets supported in any suitable manner at the opposite ends of the base, and as they are of similar construction a description of one will answer for both. The armature 20 of the magnet e⁸ has an upright armature-lever n⁴, suitably pivoted at 21 to the base and drawn normally away from the magnet by a spring 22, whose tension is adjusted by a screw 23 in the usual manner. When the magnet is energized, the upper end of the lever n⁴ makes contact through its point 24 with a point e⁸, but when the magnet is deenergized the lever falls back against an insulated stop or screw 25.

On the outer side of the lever is a lug 26, so located that when the lever falls back the outer end of the lug strikes and rides up an incline 27 on the adjacent end of the bar 8, thereby depressing this end of the bar against the tension of spring N³ and raising the opposite end of the bar, so that spring E³ is lifted by its hook 10 off the post E⁴ and the flat portion 28 at the highest end of the bar is raised to a point opposite the lug 26 on the other armature-lever n⁴, as seen in dotted lines in Fig. 1. Thereafter, if the magnet e⁸ is deenergized and its armature-lever n⁴ falls away, it is obvious that it can fall only a slight distance, because its lug 26 will strike the flat portion 28 on the then raised end of the bar 8. On

reenergizing the magnet n^8 its lever e^4 will be again attracted and the lug will move off the inclined portion 27 at the then lower end of the bar 8, so that the spring N^3 will throw the lever again into a horizontal position with both lugs free and both springs resting on their posts.

If the screw 4 be loosened, it will be obvious that the entire bar 8, with its springs 10 E^3 and N^3 , can be turned on a vertical pivot, so that the cylindrical stem 3 turns slightly in the socket 1, the screw moving in the slot 2, and after adjustment the screw is again tightened; but it is to be understood that 15 said springs E^3 and N^3 are broad enough so that during such turning they do not pass off the points of the posts E^4 and N^4 .

Fig. 2 is a plan view of this repeater complete, and it illustrates the bar 8 as having 20 been so turned. It will be noticed that the turning of the bar throws its ends out of vertical alinement with the armature-levers, and therefore if those levers are afterward moved by deenergizing their magnets it will be clear that their lugs 26 will not engage the inclined or flat portions at the ends of the bar 8. Hence the turning of the bar in this manner throws it entirely beyond a point where it would be rocked or controlled in any 25 manner by the magnets, and if it cannot be rocked it is obvious that the springs make constant electrical contact with their respective posts. At any time desired the screw 4 can be loosened and the bar turned back to 30 its original position. The purpose of this turning will appear below.

The running of currents as employed in connection with the above-described repeater is as follows:

40 The four letters, "N," "S," "E," and "W" designate, respectively, the operators to the north, south, east, and west, from which points the wires lead to my repeater, which we will suppose is at the crossing of the north-south wire with the east-west wire.

45 SN is the switchboard on the north-south wire, and SE is that on the east-west wire. The wire from the south leads from its switchboard SN at the point n , thence, as at n' , to 50 a binding-post in the base of the repeater, thence, as at n^2 , to the point n^3 , thence down the lever n^4 and through the pivot 21, thence by wire n^5 to a point n^6 on the switchboard, and thence by wire n^7 through the coils of 55 the magnet n^8 and on to the north. From the switchboard SN a branch circuit leads from the point N by wire N' to a binding-post in the base of the repeater, thence by wire N^2 to the spring N^3 , to post N^4 , and thence by 60 wire N^5 to a point N^6 on the switchboard, which is plugged to connect with the point n^6 , and thence by wire n^7 through the coils n^8 and on to the north.

65 Thus it will be seen that the north-south current has two paths through this repeater—one from the switchboard, by the wires n' and n^5 , through the armature-lever of the magnet

e^8 , and the other, by wires $N' N^5$, through the spring N^3 of the rocking bar 8. The east-west wire is exactly a counterpart of the north-south—that is to say, coming in from the west it leads through e , wires e^1 and e^2 , point e^3 , lever e^4 , wire e^5 , plug e^6 , wire e^7 , and magnet-coils e^8 onto the east, and the branch leads from the switchboard SE through plug E, 70 wires E' and E^2 , spring E^3 , post E^4 , wire E^5 , plug E^6 , plug e^6 , wire e^7 , and magnet e^8 onto the east.

Supposing now that north desires to communicate with some person on the east-west 80 line. In the first place south may be cut out, if desired, and north connected with ground, which is done by suitable plugging, as will be understood. The switchboards are also suitably plugged to make the connections 85 described below and the operation is as follows: North opens his key, thus breaking the circuit on line n^7 and allowing the lever e^4 to fall back under the pressure of its spring 22. In so falling back the lug 26 strikes the inclined 90 portion 27 at the right end of the bar 8, and the latter is rocked to the position indicated in dotted lines. When the lever falls back, the circuit $e^1 e^5$ is broken between the points 95 24 and e^3 , and hence the east-west circuit is complete only through the branch $E' E^5$; but as the bar 8 moves to the dotted position shown spring E^3 rises from contact with post 100 E^4 , and hence this branch of the east-west line is broken. Therefore when north opens 105 his key the east-west line is broken. Such breaking of the east-west line deenergizes magnet e^8 and its lever n^4 is drawn by its spring 22 away from point n^8 , but as the bar 8 stands in dotted position it is obvious that 110 the lug 26 will strike the flattened portion 28 at the then higher end of the bar. The movement of this bar away from the point n^8 breaks the circuit $n^1 n^5$, but the north-south line still has another complete path from the switchboard SN through the circuit $N' N^5$ and spring N^3 , which latter, though raised from its hook 115 10, rests on its post N^4 . North now closes his key and the current flows in through magnet n^8 , wire n^7 , branch $N' N^5$, and onto the south, 120 or to the ground if south be cut out. The magnet n^8 then attracts its armature, which moves lever e^4 to the full-lined position of Fig. 1, thereby closing the circuit $e^1 e^5$ through the points 24 and e^3 , and hence closing all the 125 instruments in the east-west line. As the lever e^4 thus rises, its lug 26 releases the right end of the bar 8, and the latter resumes its horizontal position, so that spring E^3 makes contact with post E^4 , and the branch circuit $E' E^5$ in the east-west line is also closed. The current now flowing through the wire e^7 causes 130 magnet e^8 to draw the lever n^4 away from the left end of the rocking-bar 8. Thus it will be seen that north can communicate with east and west, or with either east or west if the other be cut out, and south may be meanwhile cut out or not, as desired, and obviously the same would be true of any other point or

points of compass which are connected with this instrument. In this manner my invention can be used to telegraph from one point to any other.

5 Supposing now that north and south wish to communicate with each other, but desire to cut out east and west, set-screw 4 is loosened and the stem 3 is turned in the socket 1, so that the bar 8 assumes the position shown 10 in Fig. 2, and thereafter any current on line n^7 which causes magnet n^8 to move its lever e^4 will open and close the circuit $e' e^5$; but the lug 26 will not engage the inclined portion 15 27 of the bar 8, and hence the latter will not be rocked, and its springs $E^3 N^8$ will make constant contact with their respective posts. The bar 8 being thus turned, line n^7 is still complete to the south through plugs $N N^6$, branch $N' N^5$, spring N^8 , and post N^4 , and 20 hence north and south could telegraph to each other. As the current in the line n^7 would open and close the circuit $e' e^5$, which is in the east-west line e^7 , the plugs $e e^6$ are removed, so that east and west are partially 25 cut out, although they still have a complete circuit through the branch $E' E^5$ and spring E^3 . In the same manner east and west can communicate with each other and north and south can be cut out. In this manner my 30 invention can be entirely cut out by simply turning the bar 8.

Supposing now (under the above conditions) that a local instrument is desired in the north-south line, plugs are inserted in the 35 switchboard SE at the points $L' L^2$, whereby the circuit $e' e^5$ is connected with a local circuit l , which leads through a local battery and instrument LN, and thereafter magnet n^8 and circuit $e' e^5$ will act as a repeater and 40 will duplicate on the local instrument the messages between north and south. In the same manner the messages between east and west could be duplicated by suitably plugging the switchboard SN to another local circuit l' and its instrument. (Not shown, but 45 which will be understood.) In this manner my invention can be used in the place of two repeaters.

Supposing now that the north-south line is 50 quite long and it is desired to insert a relay therein to give the current from north to south additional strength, the bar 8 is turned as in Fig. 2, and plugs n, n^6 , and N are removed, and the current on line n^7 will have 55 a path through plug N^6 and branch $N' N^5$ back to the switchboard SN, whence it will be plugged to the ground in the usual manner. Plugs $e e^6$ are now removed, whereby the magnet n^8 (which is operated by the current in 60 line n^7) becomes a relay, and hence by suitable plugging (not shown, but which will be clearly understood) south can be connected with wire e^5 , and wire e' can be led through a relay-battery to the ground. Thereafter 65 each impulse on the line from the north will energize magnet n^8 and will close a circuit from the ground through this relay-battery,

through circuit $e' e^5$, and on to the south. In the same way a relay can be inserted in the east-west line. In this manner my invention 70 may also be used in the place of two relays.

In addition to the above it will be obvious to those skilled in the art that local batteries, sounders, keys, switches, and lightning-arresters may be inserted in the several main 75 lines in the usual manner at will. It will also be obvious that various changes in the precise details of construction may be made without departing from the spirit of my invention. 80

What is claimed as new is—

1. In an instrument of the character described, a tubular socket, an upright stem rotatably mounted therein, a bar pivoted to the stem, and an electromagnet for rocking said 85 bar on its pivot when the stem is turned to one position, as and for the purpose set forth.

2. In an instrument of the character described, a tubular socket, an upright stem rotatably mounted therein, a bar pivoted to the 90 stem, a spring on the bar, a post with which said spring is adapted to make contact when the bar is turned to either position, and an electromagnet for rocking said bar on its pivot when the stem is turned to one position, as 95 and for the purpose set forth.

3. In an instrument of the character described, a tubular socket having a transverse slot in one side, a cylindrical stem mounted 100 loosely in said socket and having a forked end, a set-screw passing through the slot and taking into the stem, a rocking bar having a journal pivoted in the fork of the stem, a circuit which the bar opens and closes in rocking, and devices for rocking the bar when it 105 is turned to one position, as and for the purpose set forth.

4. In an instrument of the character described, a tubular socket having a transverse slot in one side, a cylindrical stem mounted 110 loosely in said socket, a set-screw passing through the slot and taking into the stem, a rocking bar pivoted to the stem, a circuit which the bar opens and closes in rocking, a spring for normally closing said circuit when 115 the bar is turned to either position, and devices for rocking the bar when it is turned to one position, as and for the purpose set forth.

5. In an instrument of the character described, a rotatably-mounted stem, a bar pivoted to the stem so as to rock, a circuit which the bar opens and closes in rocking, and means for rocking the bar when it is turned to one position, as and for the purpose set forth. 120

6. In an instrument of the character described, a rotatably-mounted stem, a bar pivoted to the stem so as to rock, a circuit which the bar when turned to either position opens and closes in rocking, and means for rocking the bar when it is turned to one position, as 125 and for the purpose set forth.

7. In an instrument of the character described, a rotatably-mounted stem, a bar pivoted to the stem so as to rock, a circuit which

the bar opens and closes in rocking, and an electromagnet for rocking the bar when it is turned to one position, as and for the purpose set forth.

5 8. In an instrument of the character described, a rotatably-mounted stem, a bar pivoted to the stem so as to rock, a circuit which the bar when turned to either position opens and closes in rocking, and an electromagnet 70 for rocking the bar when it is turned to one position, as and for the purpose set forth.

9. In an instrument of the character described, a bar mounted on a central pivot, a hook depending from each end, a spring connected with but insulated from each arm of the bar and normally resting on said hook, and posts normally in contact with both and always in contact with one of said springs, combined with means for depressing either 80 end of the bar, as and for the purpose set forth.

10. In an instrument of the character described, a bar mounted on a central pivot, a hook depending from each end, a spring connected with but insulated from each arm of the bar and normally resting on said hook, and posts normally in contact with both and always in contact with one of said springs, combined with an electromagnet for depressing either 85 end of the bar, as and for the purpose set forth.

11. In an instrument of the character described, a bar mounted on a central pivot, a hook depending from each end, a spring connected with but insulated from each arm of the bar and normally resting on said hook, and a post with which each spring normally contacts; combined with devices for depressing either end of the bar, and means for turning 90 the bar in a plane at right angles to the plane in which it rocks and away from the action of said devices for depressing it, as and for the purpose set forth.

12. In an instrument of the character described, a pivoted bar having an inclined portion at its free end, and a circuit controlled by the rocking of the bar; combined with a lever having a lug engaging said inclined portion of the bar for rocking it, and an electromagnet 95 for moving said lever, as and for the purpose set forth.

13. In an instrument of the character described, a centrally-pivoted rocking bar having at each end an inclined portion and a flattened portion, and means for holding the bar normally horizontal; combined with a lever at each end of the bar having a lug standing opposite the inclined portion and adapted when moved to depress this end of the bar 100 and to raise the other end so that the flattened portion thereof is brought opposite the other lug, as and for the purpose set forth.

14. In an instrument of the character described, a pivoted bar having at its free end 105 an inclined portion and a flattened portion, a spring supporting this end yieldingly in normal position, and means for raising such end

when desired; combined with a lever having a lug standing opposite the inclined portion when the bar is in its normal position but 70 striking the flattened portion when it is raised, as and for the purpose set forth.

15. In an instrument of the character described, two electromagnets, and inwardly-projecting lugs on their armature-levers; combined with a centrally-disposed stem capable of being turned, a rocking bar pivoted to said stem and having at each end an inclined portion and a flattened portion standing in upright alignment with said lugs but thrown out 80 of such alignment when the stem is turned, springs holding the bar normally horizontal with its inclined portions opposite and its flattened portions below said lugs, posts with which said springs normally contact when the 85 bar is turned to either position, and a circuit in which each spring and its posts are included, as and for the purpose set forth.

16. The combination with an electromagnet having a lug on its armature, a pivoted 90 bar adapted to be rocked by said lug, a spring connected with the bar, a post with which said spring contacts when the bar is in its normal position, and a circuit whose wires lead to said spring and post; of a second circuit through 95 said electromagnet, as and for the purpose set forth.

17. The combination with an electromagnet having a lug on its armature, a pivoted 100 bar adapted to be rocked by said lug when 100 the magnet is deenergized, and a circuit through said electromagnet; of a spring on the bar, a post with which the spring contacts when the bar is in its normal position, a circuit connected with said spring and post, and 105 a branch from this circuit connected with said armature and adapted to be closed when its electromagnet is energized, as and for the purpose set forth.

18. The combination with two electromagnets having lugs on their armatures, an interposed pivoted bar adapted to be rocked in one direction when either magnet is deenergized, a spring on said bar, and a post with which said spring normally contacts; of a circuit 110 through one magnet and closed by the armature of the other magnet when the latter is energized, a branch from this circuit connected with said spring and post, and a second circuit through the other magnet and closed by 115 the armature of the first magnet when the latter is energized, as and for the purpose set forth.

19. The combination with two electromagnets, pivoted levers connected with their armatures and having inwardly-projecting lugs, a centrally-pivoted bar mounted between said levers so that it may be turned out of alignment with said lugs or into alignment therewith to be depressed at one end by the deenergization of the adjacent magnet, springs secured beneath the opposite arms of said bar, and posts with which said springs normally contact when the bar is turned to either 120 125 130

position; of a circuit through one magnet and through the armature of the other magnet, so as to be closed when the latter is energized, a branch from this circuit through the spring and its post which are remote from said magnet, a second circuit through this magnet and the armature of the other magnet, so as to be closed when the latter magnet is energized, and a branch from this circuit through the re-

maining spring and post, all as and for the purpose specified.

In testimony whereof I have hereunto subscribed my signature on this the 20th day of December, A. D. 1893.

ALBERT EDWARD COLLYER.
